Primary Examiner — Dominic Simone(74) *Attorney, Agent, or Firm* — Baker & McKenzie LLP(57) **CLAIM**

The ornamental design for a shoe, as shown and described.

DESCRIPTION

FIG. 1 is a left side elevational view, with the upper panel attached and the tongue extended, of a shoe showing my new design;

FIG. 2 is a top plan view thereof with the upper panel attached and the tongue extended;

FIG. 3 is a right side elevational view thereof with the upper panel attached and the tongue extended;

FIG. 4 is a bottom plan view thereof with the upper panel attached and the tongue extended;

FIG. 5 is a front perspective view thereof with the upper panel attached and the tongue extended;

FIG. 6 is a rear perspective view thereof with the upper panel attached and the tongue extended;

FIG. 7 is a left side elevational view thereof with the upper panel detached and the tongue folded;

FIG. 8 is a right side elevational view thereof with the upper panel detached and the tongue folded;

FIG. 9 is a front perspective view thereof with the upper panel detached and the tongue folded;

FIG. 10 is a rear perspective view thereof with the upper panel detached and the tongue folded; and,

FIG. 11 is a top plan view thereof with the upper panel detached and the tongue folded.
